UNITED STATES PATENT OFFICE.

SAMUEL J. LEVY, OF JOHNSTOWN, PENNSYLVANIA.

SLEIGH-RUNNER FOR VEHICLES.

1,128,698.

Specification of Letters Patent.

Patented Feb. 16, 1915.

Application filed March 9, 1914. Serial No. 823,311.

To all whom it may concern:

Be it known that I, SAMUEL J. LEVY, a citizen of the United States of America, and a resident of Johnstown, Cambria county, 5 and State of Pennsylvania, have invented certain new and useful Improvements in Sleigh-Runners for Vehicles, of which the following is a specification, reference being had to the accompanying drawings, forming a part thereof.

My invention relates to wheeled vehicles and it has special reference to baby carriages, go-carts, and the like.

One object of my invention is to provide 15 a simple, adjustable and improved sleigh-runner attachment for wheeled vehicles.

Another object is to provide an attachment of the aforesaid character that shall be adapted to be set in either of two predetermined 20 positions to perform the respective functions of a sleigh-runner and a mud guard.

Still another object is to provide an attachment that shall permit a limited rotative adjustment of the body of the vehicle 25 relative to the plane of the runner, whereby it is particularly adapted for use on two-wheeled vehicles.

Other objects and advantages of my invention will be set forth hereinafter and in order that my invention may be thoroughly understood, I will describe my invention in the following specification and then point out the novel features thereof in appended 35 claims.

Referring to the drawings: Figure 1 is a side elevation of a go-cart equipped with the attachment of my invention. A detailed perspective of the attachment with some of its parts separated, is shown on a larger scale in Fig. 2. Fig. 3 is a side elevation showing the same attachment applied to a four-wheeled vehicle. Fig. 4 is a view corresponding to Fig. 1 of a four-wheeled vehicle equipped with a modified form of runner attachment which also embodies my invention. A perspective of this form of attachment is shown on a larger scale in Fig. 5. Fig. 6 is a front view of a 45 wheel and a portion of its axle, with the attachment of Figs. 4 and 5 shown in section.

Like characters of reference designate corresponding parts in all the figures.

With special reference to Figs. 1 and 2, 55 10 represents the body of a two-wheel go-cart or carriage of which 11 is the axle and 12 one of the wheels. The body is supported from the axle by a frame 13 or other suitable means, and a handle 14 is provided 60 by which the vehicle may be drawn. The structure of the attachment, which is clearly shown in Fig. 2, will first be discussed in detail, and comprises a pair of clamping blocks 15 and 16, each of which is provided 65 with a notch 17 to engage the axle 11 and has a semi-cylindrical outer surface 18 from which extends a pin 19. A brace 20 having a cylindrically curved section 21 in which is a slot 22 and an overturned end 23, 70 75 is adapted to fit over the block 15. Another brace 25 has a cylindrically curved section 26, which is adapted to co-operate with the block 16 and an overturned end 27 corresponding to the end 23 of the brace 20. 75 The curved sections of the braces are adapted to surround the blocks and hold them in position on the axle 11 as shown in Fig. 1, the braces being secured together by bolts 28. The section 26 of the brace 25 has a 80 slot 29 corresponding to the slot 22, the pins 19 of the blocks being arranged to extend through the respective slots and to hold the blocks in position. The straight portion 85 of each of the braces 20 and 25 is made in two sections which are adjustably connected together in any suitable manner. For example,—the strip 20 is provided with a screw or bolt 32 which extends through a slot 33 in a section 20^A and is screwed into a 90 section 20^B, a U-shaped guide 34 being secured to section 20^A and extending over the edges of the other section. Affixed to the overturned ends 23 and 27 are a pair of laterally extending bars 30 and 31, which are 95 made adjustable in a manner similar to that of the braces. The rod 31 is similarly constructed and need not be described in detail, the arrangement of each rod being such that its length may be determined by adjusting 100 its two parts relative to each other, and setting the bolt which holds them together. Depending from the outer ends of the bars 30 and 31 are a pair of sleigh-runner members 36 and 37. The member 36 has an upwardly extending end 38 which is adjustable as to its length and is pivotally connected to the bar 30. In like manner the 105

member 37 has an adjustable section 39 and is pivotally connected to the bar 31. The members 30 and 38 are joined by a spring 39 which, when the two members are in alignment, intercepts the pivotal axis at their point of connection. Consequently the spring tends to hold the sleigh-runner either in the position shown in Fig. 2 against a stop 40 or in a position at 180 degrees thereto against a stop 41. The members 31 and 38 may also be connected by a spring (not shown) to assist the spring 39. The runner portion of the member 37 is offset at 42 to overlap a portion of the member 36 and is provided with a slot 43 through which clamping screws 44 extend. These screws engage tapped holes in the member 36 and when loosened hold the members 36 and 37 in alignment with each other while permitting the elongation or contraction of the runner. When the runner is adjusted to suit the vehicle with which it is used, the screws 44 are set.

From the foregoing, the application of the device to a vehicle such as that shown in Fig. 1, will be readily understood. Attention is directed to the fact that the runner is adjustable not only to the size of the vehicle wheel but its position may also be changed according as it is desired to operate the vehicle on runners or on wheels without removing the runner attachment. The runner is made relatively broad and flat in order that it may constitute a mud guard when in its elevated position, and when the vehicle is being operated on wheels. It is shown in this position in broken lines in Fig. 1. The spring 39 serves to prevent the parts from rattling and determines the two operative positions of the runner.

One of the advantages of a two-wheel vehicle arises from the fact that the body and frame may be swung about the center of the axle as a pivot. This advantage is maintained by the use of the sleigh-runner attachment of my invention since the slots 22 and 29 permit the vehicle body and frame to be swung about the center of the axle as a pivot, the blocks 15 and 16 which act as a unit being arranged to turn with the axle in the sleeve formed by the cylindrically curved sections 21 and 26. While I have shown only a single runner attachment, one will of course be applied to each wheel of the vehicle; in fact, the same attachment may be utilized for four-wheel vehicles as shown in Fig. 3.

Referring to Figs. 4, 5 and 6, the modification here shown is similar to that of the previous figures except that it is particularly adapted for use on four-wheel vehicles where no tilting of the body about either axle center is required. A pair of similar braces 50 and 55 replace the braces 20 and 25 and each of them comprises a clamp 51 which

is adapted to rigidly engage one of the vehicle axles and each of them is adjustable as to its length. The runner members 56 and 57 are preferably provided with clips 58 and 59 to engage the respective vehicle wheels. Each of these clips is arranged to swing on a pivot 60 and is held either in an active position or flat against the runner by a spring 61. It may therefore be swung out of the way when the runner is used as a mud guard. A further description of this modification is unnecessary because other parts correspond to the structure already described. Attention is particularly directed to the fact that the adjustments permitted in the length of the members 50 and 55 and in the runners are such as to enable the attachment to be set for vehicles of quite widely varying wheel bases and the other adjustments which have already been discussed in connection with the previous figures, enable the device to be set for a vehicle having wheels of different sizes. In this modification, as in the previous arrangement, the runner may be adjusted to a position above the wheels to constitute a mud guard. Thus it is evident that the attachment when once applied may be not only left in position indefinitely but is always of service in one capacity or the other. Furthermore, it enables the vehicle to be quickly converted to a sleigh or vice versa with small effort and without the use of any tools.

My structure is an improved article of manufacture which may be produced in large quantities at a relatively small expense, and is arranged to avoid the necessity for carrying more than one size for vehicles of any one class.

While I have shown my runner attachment in connection with a baby carriage or go-cart, it is not limited in this regard and of course may be utilized in connection with vehicles of every description.

What I claim is:

1. An attachment for wheeled vehicles comprising a segmental clamping block having a substantially cylindrical outer surface and adapted to be mounted on a wheel axle adjacent to a wheel, braces having co-operating curved portions rotatively mounted on the block and extending longitudinally of the vehicle in opposite directions beyond the wheel rim, lateral bars secured to the respective ends of the braces, and a sleigh runner pivotally connected to the lateral bars in the plane of the wheel and adapted to be swung under the wheel or above it to constitute either a sleigh-runner or a mud guard.

2. An attachment for wheeled vehicles comprising a clamping block adapted to be mounted on a wheel axle, braces having co-operating socket portions rotatively mounted on the block and extending beyond the wheel rim, laterally extending bars secured

to the respective ends of the braces, and a sleigh-runner pivotally connected to the bars in the plane of the wheel.

3. An attachment for wheeled vehicles comprising a clamping block adapted to be mounted on a wheel axle, braces having co-operating socket portions rotatively mounted on the block and extending beyond the wheel rim, and a sleigh-runner pivotally connected to the braces and adapted to be swung under the wheel or above it to constitute either a sleigh-runner or a mud guard.

4. An attachment for wheeled vehicles comprising a clamping block adapted to be mounted on a wheel axle, braces having co-operating socket portions rotatively mounted on the block and extending beyond the wheel rim, a sleigh-runner pivotally connected to the braces and adapted to be swung under the wheel or above it to constitute either a sleigh-runner or a mud guard, and means for holding the runner in either of said positions.

5. An attachment for wheeled vehicles comprising a clamping block adapted to be mounted on a wheel axle, braces having co-operating socket portions rotatively mounted on the block and extending beyond the wheel rim, a sleigh-runner pivotally connected to the braces and adapted to be swung under the wheel or above it to constitute either a sleigh-runner or a mud guard, and means for limiting the rotative movement of the braces and the runner on the block.

6. An attachment for wheeled vehicles comprising a clamping block adapted to be mounted on a wheel axle, braces having co-operating socket portions rotatively mounted on the block and extending beyond the wheel rim, a sleigh-runner pivotally connected to the braces and adapted to be swung under the wheel or above it to constitute either a sleigh-runner or a mud guard, and means for guiding and limiting the rotative movement of the braces and the runner on the block.

7. An attachment for wheeled vehicles comprising a clamping block adapted to be mounted on a wheel axle, braces having co-operating socket portions rotatively mounted on the block and extending beyond the wheel rim, a sleigh-runner pivotally connected to the braces and adapted to be swung under the wheel or above it to constitute either a sleigh-runner or a mud guard, means for holding the runner in either position, and means for limiting and guiding the rotative movement of the braces and the runner on the block.

8. An attachment for wheeled vehicles comprising a segmental clamping block having a substantially cylindrical outer surface, and pins extending outwardly from opposite points on said surface and adapted to be mounted on a wheel axle adjacent to a wheel,

braces having co-operating curved portions provided with circumferential slots rotatively mounted on the block with said pins in engagement with said slots and extending longitudinally of the vehicle in opposite directions beyond the wheel rim, and a sleigh-runner pivotally connected to the braces.

9. An attachment for wheeled vehicles comprising a segmental clamping block having a substantially cylindrical outer surface and pins extending outwardly from opposite points on said surface and adapted to be mounted on a wheel axle adjacent to a wheel, braces having co-operating curved portions provided with circumferential slots rotatively mounted on the block with said pins in engagement with said slots, and adjustable straight portions extending longitudinally of the vehicle in opposite directions beyond the wheel rim; and a sleigh-runner pivotally connected to the braces and adapted to be swung under the wheel or above it to constitute either a sleigh-runner or a mud guard.

10. An attachment for wheeled vehicles comprising a segmental clamping block having a substantially cylindrical outer surface, and pins extending outwardly from opposite points on said surface, and adapted to be mounted on a wheel axle adjacent to a wheel, braces having co-operating curved portions provided with circumferential slots rotatively mounted on the block with said pins in engagement with said slots, adjustable straight portions extending longitudinally of the vehicle in opposite directions beyond the wheel rim, adjustable, laterally-extending bars secured to the outer ends of the braces, and a sleigh-runner pivotally connected to the bars and adapted to be swung under the wheel or above it to constitute either a sleigh-runner or a mud guard.

11. An attachment for wheeled vehicles comprising a segmental clamping block having a substantially cylindrical outer surface and pins extending outwardly from opposite points on said surface and adapted to be mounted on a wheel axle adjacent to a wheel, braces having co-operating curved portions provided with circumferential slots rotatively mounted on the block with said pins in engagement with said slots, adjustable straight portions extending longitudinally of the vehicle in opposite directions beyond the wheel rim, adjustable, laterally-extending bars secured to the outer ends of the braces, and a sleigh-runner comprising a pair of adjustably connected sections pivotally connected to the bars and adapted to be swung under the wheel or above it to constitute either a sleigh-runner or a mud guard.

12. An attachment for wheeled vehicles comprising adjustable braces adapted to be connected to vehicles of varying dimensions,

and a longitudinally adjustable sleigh-runner pivotally connected to the braces and arranged to be swung under the wheel or above it to constitute either a sleigh-runner or a mud guard.

13. An attachment for wheeled vehicles comprising longitudinally adjustable braces adapted to be connected to vehicles of varying dimensions, a longitudinally adjustable sleigh-runner pivotally connected to the braces and arranged to be swung under the wheel or above it to constitute either a sleigh-runner or a mud guard, and means for holding the runner in either of said positions.

14. An attachment for wheeled vehicles comprising longitudinally adjustable braces adapted to be connected to a vehicle, a longitudinally adjustable sleigh-runner pivotally connected to the brackets, stops for limiting the pivotal adjustment of the runner and a spring adapted to hold the runner against either one of said stops.

In witness whereof, I have hereunto set my hand in the presence of two subscribing witnesses, this 28 day of February, 1914.

SAMUEL J. LEVY.
